UNITED STATES PATENT OFFICE

HENRY E. PETERSON, OF GRAPEVIEW, WASHINGTON

GRAPE PRESS

Application filed November 12, 1930. Serial No. 495,021.

My invention relates to presses for such fruits as grapes, berries, and the like. One of the objects of my invention is to provide a press of this character of considerable capacity, yet so arranged that the bed of mash 5 is comparatively shallow, so that as a result a good pressing may be obtained with minimum pressure, resulting in the production of clear juice.

It is a further object to provide a press of 10 this type employing a short screw, so that the time and effort used to screw up and down a long screw is eliminated, and further, to provide a means whereby the 15 plunger and associated parts may be thrown back out of the way to give free access to the press box, without the necessity of employing a long screw.

A further object is the provision of a press 20 for such uses which, because of the lower pressure, will permit the use of ordinary strainer cloths, notwithstanding the use of power means to produce the pressure, yet will cause a minimum of bursting of these cloths.

25 Other objects, and more especially such as relate to the mechanical details of my invention, may be understood from a study of the accompanying drawings, wherein my invention is shown embodied in a form which is at present preferred by me, of the following specification, and of the claims which terminate the same.

30 My invention comprises the novel grape press, embodied in illustrative form in the drawings, and as described in the specification and defined by the claims.

Figure 1 is a front elevation of my press, parts being shown in section.

35 Figure 2 is a transverse section through my press, showing parts in position ready to start a press, and Figure 3 is a similar view, with the beam and associated parts in end elevation, but illustrating parts thrown open ready to receive a fresh charge of mash.

40 In order that the capacity of the press may be conveniently large, yet that the body of mash within the press be shallow, so that the pressure is communicated easily through 45 the mass, I prefer that the press box 1 be

made comparatively long as related to its width and particularly as related to its depth. It is suitably supported, as upon the frame-work 10, and between the posts 11 and 12, and these various parts are suitably braced, as is indicated by the tie-rods 13, so that the press box is tight against pressure tending to spread its walls apart. Cooperating with this press box is a plunger 2, which is of a size approximately corresponding to the press box, and fitting thereinto. This may be braced by a backbone or longitudinal rib 20.

To raise and lower the plunger 2 from the position shown in Figure 2, I provide a 55 screw 3 which is received within a nut 32, the nut being secured to the plunger or to the rib 20 by such means as the bolts 22, and the upright screw is journaled at 34 in a beam 4, which extends transversely across 60 the press box at a distance above the plunger. A thrust bearing, indicated at 30, would ordinarily be employed at the lower side of the beam, and to conserve space the rib 20 may have a hole 23 to receive the lower end 65 of the screw when parts are in the position shown in Figure 2.

To rotate the screw and to move the plunger downward, various means may be employed. I prefer to employ a motor 5, 80 mounted upon the beam, and preferably upon an overhanging extension 40 thereof, which motor is connected to a countershaft 50, whereon is secured a worm pinion 51, meshing with a worm gear 53 on the upper 85 end of the jack screw 3.

Because of the length of the plunger 2, I prefer that two or more jack screws 3 be employed, and to support them, I may employ 90 a corresponding number of beams 4, which may be suitably braced, as indicated at 41, so that they move as a unit. They may also be connected by a board 45 which forms a platform for the reception of the motor 5. The countershaft 50, in such a case, would 95 extend longitudinally of the press box 1, but above it on that portion 42 of the beams which normally lies above the press box and plunger. Suitable bearings 52 are provided for the opposite ends of the countershaft,

- these being supported, in the arrangement shown, upon angle brackets 43. Naturally, there would be one of the worm gears 53 and a corresponding worm 51 for each of the 5 screws 3, and suitable means would be arranged to drive the countershaft from the motor, such as the belt 54 passing over pulleys 55 and 56. All of this power drive mechanism is, therefore, supported upon the beams.
- 10 Unless a long screw 3 is employed, it is not an easy matter to raise the plunger sufficiently that convenient access may be had to the interior of the press box to supply additional mash, to place it within the strainer 15 cloth, or to remove or shift the pressed mash, and inasmuch as it is desirable to do this frequently, and quickly, I provide a means in the mounting of the beam 4 whereby the plunger may be quickly and easily swung to 20 one side out of the way, and I do this by providing a pivot support at 44 approximately at the level of the top of the press box 1, and at one side thereof, which pivot support directly engages a depending leg 46 secured to 25 the beam 4 between its ends; to hold parts in position and to take the stresses incident to the pressing operation, I provide another depending leg 47 depending from the front end 42 of the beam. The leg 46 is pivoted upon 30 the post 12 and the leg 47 is secured temporarily to the upper end of the post 11, this connection being broken by means of the removable pin 48.
- 35 Normally, parts will be substantially balanced at either side of the pivot 44, the weight of the motor nearly if not quite counterbalancing the weight of the screws, plunger and drive means. When it is desired to gain access to the press box, the pin 48 is withdrawn, and the beam 4 tilted backward from 40 the position of Figure 2 to the position of Figure 3. The effort required to start this tilting is not great, owing to the balance of the parts, but because of the fact that the 45 center of gravity of the beam as a whole is well above its pivot 44, the tilting quickly accelerates, and it is necessary to provide a means whereby the rear end 40 of the beam will not strike the floor or any buffer too 50 heavy a blow. Any convenient means may be employed for this purpose, but I have found it convenient to connect the end 40 by a cable 60 to a quadrant 61, from which there 55 normally depends a counterweight 6.
- 55 The quadrant is in effect a wheel, though only one-fourth of this periphery is employed, and it is supported, as by a bracket 62, from the ceiling or any other overhead support. The peripheral distance about 60 one-quarter of this wheel, that is, about the useful quadrant, is the same as the distance through which the end 40 of the beam moves between its upper and its lower position. As 65 the beam swings into tilted position, therefore, the cable 60, the upper end of which is

secured to the quadrant or wheel 61, pulls upon the quadrant and upon the counterweight 6, and moves it from a normally depending position, as indicated in Figure 2, to a position projecting laterally from the support of the pivot, and in this movement its 70 resistance increases from nothing to the resistance offered by the given weight at the selected leverage, which is the distance of the weight from the pivot center of the quadrant. 75 This checks the tilting of the beam.

It will be understood that all parts would be sufficiently braced, and to this end while I may employ wooden beams, I will reinforce such as bear the heavy stresses with strap iron 80 or like material.

With the press in the position shown in Fig. 3, the nut 32 is fully retracted to the upper end of the screw 3, and the plunger is clear of the press box. The strainer cloth 7 85 is in position in the press box, and would usually rest upon a slat-like structure 70, which supports the strainer cloth and the mash somewhat above the bottom of the press box. The mash is now poured into the strainer cloth within the press box, this is thrown over the top of the mash and over the ends to enclose it completely, and the beam is tilted back to the position of Figure 2, where the pin 48 is inserted, and the parts 90 are now in the position of Figure 2. Upon starting the motor, the screws 3 rotate at the same rate of speed and the plunger 2 moves downwardly into the press box to express the juice from the fruit. Since the screw 3 is 100 short, but little movement is required, and because of the employment of a number of screws and a shallow box, the pressure is distributed evenly over the surface of the mass and throughout the volume thereof. As a result, the pressure at any given point is not great, the juice is expressed by steady pressure, and comes through the strainer cloth without carrying any considerable amount of the fruit pulp, yet a high percentage of the juice is pressed out. Because the pressures are not high, bursting of strainer cloths 105 is rare, and the juice, not being forced through a strainer cloth at high pressure, does not tend to squirt out of the press box and upon the floor, keeping the surrounding of 110 the press clean.

The press box would ordinarily be inclined slightly, so that the juice will run to one end, and there is a hose connection, as indicated at 8 in Figure 1, at this end, through which the juice is run off into a settling vat, or the like.

What I claim as my invention is:

1. A grape press comprising a press-box, 125 a plunger receivable therein, a beam normally disposed over the plunger, a pivot support for the beam between its ends, at one side of the press-box and below the beam, an upright screw journaled in that end of the beam 130

which extends over the plunger, power means for rotating said screw including a motor carried by the opposite end of the beam, and a nut secured upon the plunger and receiving the lower end of the screw, the plunger moving, when the beam is tilted, to one side of the press-box.

2. A grape press comprising a press-box, a plunger receivable therein, a beam normally disposed over the plunger, a pivot support for the beam between its ends, at one side of the press-box and below the beam, an upright screw journaled in that end of the beam which extends over the plunger, power means for rotating said screw including a motor carried by the opposite end of the beam, a nut secured upon the plunger and receiving the lower end of the screw, the plunger moving, when the beam is tilted, to one side of the press-box, and a counterweight connected to the beam to compensate for the shifting of weights as the beam tilts.

3. A grape press comprising a press-box, a plunger receivable therein, a beam normally disposed over the plunger, a pivot support for the beam between its ends, at one side of the press-box and below the beam, an upright screw journaled in that end of the beam which extends over the plunger, power means for rotating said screw including a motor carried by the opposite end of the beam, a nut secured upon the plunger and receiving the lower end of the screw, the plunger moving, when the beam is tilted, to one side of the press-box, a quadrant supported above the beam to swing, and having a peripheral length about equal to the travel of the beam end as it tilts, a cable secured to the beam end and passing over said quadrant, and a weight secured to the quadrant, and depending vertically when the beam is level, but projecting laterally when the beam is tilted, to counterweight the beam and the parts supported thereon.

45 Signed at Seattle, Washington, this 6th day of November, 1930.

HENRY E. PETERSON.
